UNITED STATES PATENT OFFICE

129,901

DESIGN FOR A MAILBOX

Clarence L. Hanson and Henry J. Jadin, Green Bay, Wis., assignors to Henry J. Jadin, Harris Gigot, and Clarence L. Hanson, copartners, doing business as Acme Products Company, Green Bay, Wis.

Application December 12, 1940, Serial No. 97,276

Term of patent 14 years

To all whom it may concern:

Be it known that we, Clarence L. Hanson and Henry J. Jadin, citizens of the United States, residing at Green Bay, in the county of Brown and State of Wisconsin, have invented a new, original, and ornamental Design for a Mailbox, of which the following is a specification, reference being had to the accompanying drawing, forming a part thereof, and in which

Fig. 1 is a front view of a mailbox showing our new design;

Fig. 2 a side view; and

Fig. 3 a top plan view.

We claim:

The ornamental design for a mailbox, as shown.

CLARENCE L. HANSON.
HENRY J. JADIN,
